UNITED STATES PATENT OFFICE

1,967,105

ROOFING

Herman Lee Seymour, Jacksonville, Fla., assignor
to The Philip Carey Manufacturing Company,
a corporation of Ohio

Application December 9, 1929, Serial No. 412,600

3 Claims. (Cl. 108—26)

My invention relates to roofings, particularly to what are known as built-up roofings in which sheets of roofing material are applied to a roof deck in one or more layers cemented together. 5 It is addressed especially to roofings applied to a structure where there is a roof deck and a parapet wall or other adjacent vertical structure requiring flashings.

By my invention, I provide a system of flashing 10 that insures against leakage between the roof deck and the wall, maintains the flashing in position, provides for irregularities in wall or deck, overcomes breakage of the roof at the intersection between a roof deck and adjacent walls, or 15 adjacent angular portions of the structure, is sufficiently plastic to absorb vibration, compensates for expansion or contraction, and provides a highly efficient flashing system economical to apply and one that will remain waterproof and 20 watertight.

In the drawings:

Fig. 1 shows the preferred form of my built-up roofing and flashing system applied, with portions removed to clearly show the method of 25 application.

Fig. 2 shows a modification of a portion of Fig. 1.

Fig. 3 is a modification of a portion of Fig. 1 showing a metal counter flashing. 30 Fig. 4 is a section of my counter flashing material.

Fig. 5 is a view of my eave, outlet or corner flashing block.

Fig. 6 is an enlarged view showing the layout of 35 the cant strip and the adjacent sheet members.

In the drawings, I have shown my invention as applied to a wood deck but I would have it understood that same may be applied to any type of deck such as a concrete, or brick, or any type 40 of parapet wall such as concrete or brick, or any other type of deck or parapet wall, or to any roof deck and adjacent wall or structure as the type of such structures do not form any part of my invention.

45 In the drawings in which like characters or like numerals refer to like parts, 1 is a roof deck, 2 an adjacent parapet wall. Over the roof deck and extending up the vertical wall is applied a sheet of suitable flexible roofing 3 which 50 may be cemented by bituminous cement or otherwise fastened to the roof deck and permitted to lay up against the parapet wall. As many sheets of suitable roofing may be applied as desired. At the angle between the roof deck and the parapet wall and over the roofing, I place a flashing 55

block 4 preferably using a block containing bituminous and fibrous materials preformed to the desired shape and having a plastic like form sustaining quality. This flashing block may be nailed to the wood deck, where a wood deck is 60 used, by nails passing through the block, the roof sheet and into the deck or may be cemented in place by using bituminous or other suitable cement 5. The flashing block 4 having been nailed, or cemented, or both, in place, I then apply over the 65 exposed surface of the flashing block 4, and a portion of the top surface of the roofing sheets 3 a coating of bituminous or other waterproof cement 13 into which is embedded a counter flashing sheet 6 of felted, bituminous saturated material. 70

This counter flashing sheet 6 is preferably made by cementing a sheet of bituminous saturated felt to a sheet of woven material such as burlap by an asphaltic or other bituminous cement thereby providing a strong waterproof 75 counter flashing sheet that may be stretched without breaking and that will permit movement of the adjacent parts of the roof deck and wall or either of them due to contraction or expansion without breaking this counter flashing sheet. 80

This flashing sheet shown in Fig. 4 may be made in any suitable way and of any suitable felts such as paper, wool or mineral felts 7 saturated with bituminous material and having cemented to its surface a sheet of woven textile material 85 such as burlap 9 that has been waterproofed or that may be waterproofed by the cementing material 8 and over this may be applied, if desired, a sanded or similar surfacing 10 as shown in Fig. 4 which is an enlarged cross section of 90 this sheet.

Over this counter flashing sheet 6 is then applied a coating 13 of bituminous material such as asphalt or other suitable cement extending over the counter flashing and on to the roof so 95 as to completely cover all joints and form with the coating on the roof a continuous sheet of waterproof bituminous material. In Fig. 1, I have not covered the counterflashing sheet 6 with coating 13, having omitted a portion so as to 100 clearly outline the sheet 6. I prefer to use for this coating 13 a bituminous cement containing a fibrous material such as asphalt and asbestos fibre.

In the drawings for simplicity I have shown but 105 one sheet of roofing material applied to the surface of the roof deck but of course as many sheets may be applied one above the other cemented together and secured, by cement or otherwise, to the roof deck as may be desired. Several plies of 110

counter flashing may also be applied if desired. If it were desired, the counter flashing could be extended from a nailing strip 11 in the wall 2 to which it is fastened, as shown in Fig. 2, or from 5 the top of the parapet wall, being secured under the crown 15, down over the flashing block. In the application of the flashing block 4 it may be, if desired, cemented to the roofing sheet and not to the parapet wall, or to the parapet wall and not 10 to the roof, but on a wood deck I prefer to cement it at both the top and the bottom.

In Fig. 2, I have shown a flashing block 4 especially adapted for eaves or for outlets in which the flashing block fills, when cemented in place and 15 covered with flashing sheet 6, the angle between the roof deck and the wall and provides an unobstructed passage for drainage for an outlet, shown in Fig. 1, or for an eave shown in Fig. 2 by having one or both ends cut so that the end 20 surface 16, shown in Fig. 5 is oblique to the surface 17. The end surface 16 if cut at an angle of 45 degrees to the surface 17, which is to contact with the wall, will, with the next adjacent similarly cut block, form a corner joint, shown 25 in Fig. 1, easy to apply and ready for the counter flashing or roofing sheets to be applied over same.

In Fig. 5, I have shown a detail of the block 4 showing the surface 16 at an oblique angle to the 30 surface 17 and the opposite end at the ordinary angle of 90 degrees. For some purposes I have found it an advantage to provide the portion of the block 4 when made for eave and outlet construction, with the surface 14, connecting the vertical surface 17 and the horizontal surface of the block so as to provide a space for cement and for 35 intimate contact with the roofing sheet that it sets over.

If desired, a roofing sheet material reinforced 40 as shown in Fig. 4 could be used for a base sheet of the roof and over this could be applied similar reinforced sheets or ordinary roofing material. When a plurality of sheets of roofing are applied cemented in layers on the deck so as to give a 45 roofing of several plies, one or more of the sheets or plies could be cemented on to the top surface of the flashing block 4 and the counter flashing 6 cemented on to the roofing sheets so affixed to the top of the block 4.

50 In Figure 6, I have shown a roofing in which the two layers of felt roofing are shown cemented to the deck, one layer of which, at the parapet wall, is turned up and contacts with the cant strip 4, and the upper layer of which is turned to overlap, contact with, and is cemented to, a portion of the upper surface of the cant strip 4. In this figure the cant strip is shown as cemented to the upper surface of the lower layer of roofing felt and to the parapet wall by asphalt 5. The 55 flashing 6 is affixed to the parapet wall above the cant strip and extends down over, and is cemented to, the surface of the cant strip at the upper portion, and overlaps and is cemented to the second layer of roofing material.

60 In Fig. 3, I have shown a modification using 65 a metal counter flashing 18, fixed to wall by screws 19, so arranged as to provide an apron 20 over the flashing sheet 6 and a trough 21 into which may be placed any suitable waterproof cement or filling. If desired, the ordinary metal

flashing having one edge embedded in wall and an apron extending down over the flashing sheet 6 could be used. In the application of my flashing system, the adjacent blocks may, if desired, be provided with any means to hold them in register and may be cemented together by a suitable cement 5 to form a watertight joint as shown in Fig. 1 when the corner is formed. 80

I claim:

1. In a built-up roofing, a roof deck, an adjacent wall at an angle thereto, a plurality of layers of sheet roofing material applied over the surface of the deck, a plastic form retaining block bridging the angle formed by the roof deck and the wall, said block having a surface overlapping and contacting with a portion of one layer of roofing material on the deck and another surface of said block contacting with the surface of the wall, means fixedly securing said block in position, one of the layers of flexible roofing material on the roof deck extending up over the top of the block, a flashing affixed to the wall and extending down over said block and over a portion of the layers of roofing material on the deck, said flashing being affixed to the surface of the block and to 100 the surface of the roofing material. 85

2. In a built-up roofing, a roof deck, an adjacent wall at an angle thereto, a plurality of layers of sheet roofing material applied over the surface of the deck, a plastic form retaining block 105 bridging the angle formed by the roof deck and the wall, said block having a surface overlapping and contacting with a portion of one layer of roofing material on the deck and another surface of said block contacting with the surface of the wall, means fixedly securing said block in position, one of the layers of flexible roofing material on the roof deck extending up over the top of the block, a flashing affixed to the wall and extending down over said block and over a portion of the layers of roofing material on the deck, said flashing being affixed to the surface of the block and to 110 the surface of the roofing material. 90

115

3. A built-up roofing, on a roof deck having an adjacent wall at an angle thereto, composed of a plurality of layers of prepared sheet roofing materials affixed to the surface of the deck and 120 to each other, a plastic block containing bituminous and fibrous materials preformed so as to bridge the angle formed by the deck and the adjacent wall, means securing said block in position to bridge said angle so that one surface of 125 the block overlaps and contacts with a layer of the roofing material on the deck and another surface of the block contacts with and overlaps a portion of the wall, one of the layers of roofing material on the deck overlapping another surface 130 of the block, a flashing composed of a reinforced sheet of bituminous saturated felt affixed to said wall above the flashing block and extending down over the surface of the block onto the surface 135 of the roofing material beyond the edge of the block, and means cementing said flashing to the underlying layer of roofing material. 140
